DOLL'S VOICE

Stanley Krakowski, Hoboken, N. J.

Application August 16, 1939, Serial No. 290,410

5. Claims. (Cl. 46—192)

This invention relates to sound devices and more particularly to a device for producing two tones in an articulated sound such as in the word "ma-ma," the device being for use in dolls and similar toys.

An object of the invention is to provide a sound reproducing device having a sound chamber which is opened and closed at pre-determined intervals to emit sounds of different tones.

10 Another object is to provide means cooperating with the sound making means for controlling the opening and closing of the sound chamber.

A further object of the invention is to provide a sound producing device which may be easily mounted in a doll or similar device and which when actuated will imitate the cry "ma-ma" of a baby, reproducing the two different tones of that cry.

Other objects will be obvious or will appear 20 during the course of the following specification.

In accomplishing the objects of this invention it has been found most satisfactory to provide a housing adapted to be positioned in a doll and having rotatably mounted therein a disc with a 25 serrated periphery bearing against a vibrator mounted on a sounding board. The sounding board serves as the bottom for a sound chamber which has an opening therein and a cover adapted to open and close said opening by means of 30 an actuator operated by cams on the serrated wheel.

The above and other objects will appear more clearly from the following detailed description when taken in conjunction with the accompanying drawing which illustrates a preferred embodiment of the invention.

Figure 1 is a side elevational view of the invention a doll being indicated in dot and dash lines;

40 Figure 2 is a vertical sectional view of the device;

Figure 3 is a sectional view on the line 3—3 of Figure 2; and

45 Figure 4 is a perspective view of the sound producing means and sound chamber cover actuating means.

Like numerals refer to like parts throughout the several views.

The device, in the embodiment of the invention 50 illustrated in the drawing, comprises a housing 10 having a lower portion 11 and an upper section 12.

A sound chamber 13 is formed by the upper section 12, the sound chamber having a top 14 with 55 an opening 15 therein. The bottom of the sound

chamber consists of a sounding board 16. A cover 17 cooperates with the opening 15 and is mounted on a spring strip 18 fastened to the upper section 12 which strip tends to hold the cover in a normally open position in relation to the 5 opening.

Mounted on the sounding board 16 and projecting from the underside thereof is a vibrator 19, preferably of a resilient metal which engages the serrated periphery 20 of a wheel 21, so that a sound is made upon turning the wheel 21. The periphery 20 of the wheel 21 has a portion thereof cut away to form a flat surface 29 having no serrations. The wheel 21 is fixedly mounted on a 10 crankshaft 22 which in turn is rotatably mounted 15 in the lower portion 11 of the housing 10. A crank-handle 23 formed integrally with said crankshaft extends from the housing 10.

Projecting from one surface of the wheel 21, 20 are two cams 24 and 25 which are spaced from one another and are adapted to engage extensions 26 and 27 on one side of a sound chamber cover actuator 28. An arm 30 extending from the opposite side of the actuator 28 is connected to the 25 cover 17 by means of a cord 31. The actuator 28 is pivotally supported in a mounting 32 by means of ears 33 and 34 on the opposite ends of the actuator 28 forming an axis for said actuator.

A stop 35 for limiting the pivotal movement 35 of the actuator in one direction is provided. On the outside of the housing 10, in the path of the crank-handle 23, a second stop 36 which limits the movement of the crank to one revolution in one direction is mounted.

In the operation of the device, of this invention, the same may be mounted in a doll in any suitable manner, so that the crank-handle 23 projects to the outside of the doll's body. As shown more particularly in Figures 2 and 4 of the drawing, at the start of the operation the crank-handle 23 40 is at rest in its uppermost position on one side of the stop 36, the flat surface 29 of the wheel is adjacent the vibrator 19. At this time, the actuator 28 is in a horizontal position, the top surface thereof resting against the stop 35, the cover 17 being in its open position.

As the crank-handle 23 is turned in a counter-clockwise direction, the flat portion 29 of the wheel 21 passes from the vibrator 19 and the serrated periphery 20 of the wheel engages the vibrator. Simultaneously with the engagement of the serrated periphery of the wheel 21 with the vibrator 19, the cam 24 engages the extension 26 on the actuator 28 pivoting the actuator in a counter-clockwise direction about its axis which 55

moves the arm 30 and cover 17 downwardly against the tension of the spring 18 closing the opening 15 of the sound chamber 13.

Engagement of the vibrator 19 with the serrated periphery 20 of the wheel 21 upon further movement of the crank 23 and the crankshaft 22 in a counter-clockwise direction produces the comparatively low sound of "mmm" the first sound of the syllable of the word "ma-ma" since the opening 15 of the sound chamber 13 is closed.

Upon further movement of the crank in a counter-clockwise direction, the low sound of "mmm" continues until the cam 24 passes from engagement with the extension 26 on the actuator 28, at which time the actuator 28 is moved in a clockwise direction by the action of the spring 18 allowing the cover 17 to move upwardly uncovering the opening 15 of the sound chamber. The top surface of the actuator comes to rest against the stop 35.

The engagement of the vibrator 19 with the serrated periphery 20 of the wheel 21 open further counter-clockwise movement of the crank-handle 23, since the opening 15 is uncovered, produces a comparatively higher and louder sound of "ah," the second sound of the first syllable of the word "ma-ma" until the extension 26 is engaged by the cam 25.

When the cam 25 engages the extension 26, the actuator 28 is again pivoted in a counter-clockwise direction on its axis closing the cover 17 against the opening 15. Further rotation of the crankshaft 22 in a counter-clockwise direction produces the comparatively low sound of "mmm" until the cam 25 passes from engagement with the extension 26 on one side of the actuator 28, at which time the actuator moves on its axis in a clockwise direction allowing the tension of the spring 18 to move the cover upwardly uncovering the opening 15. A higher and louder sound is then emitted from the sound chamber 13 which sound emulates the second sound, "ah," of the second syllable of the word "ma-ma." The crank-handle 23 is turned further in a counter-clockwise direction until it engages the stop 36.

Due to the spacing of the cams 24 and 25 the final sound of "ah" is of longer duration than the sound of "ah" in the first syllable of the word.

When the crank has come to rest against the stop 36, one complete revolution has been made, the parts of the device being in the position from which they started as shown in Figures 2, 3, and 4 of the drawing. In order however, that the device may again be operated, the crank-handle 23 must be turned in a clockwise direction. The operation of the parts will be similar to the operating of the same when the crank was turned in a counter-clockwise direction except that the cams 25 and 24 will engage the extension 27 on the actuator 28 to open and close the opening 15 of the sound chamber 13.

It is apparent that the specific illustration described above and set forth in the accompanying drawing has been given by way of illustration and not by way of limitation, and that the structure above described is subject to wide variation and modification without departing from the scope or intent of this invention, all of which variations and modifications are to be included within the scope of the appended claims.

What is claimed is:

1. A doll's voice comprising a sound box having an opening therein, a cover for said opening,

a vibrator attached to said sound box, a disc having a serrated periphery bearing against said vibrator, means for rotating said disc, cover actuating means and means on said disc adapted to engage said cover actuating means and move the same, opening and closing said cover at pre-determined intervals.

2. A doll's voice comprising a sound box having an opening therein, a cover for said opening, adapted to be closed against spring tension, a vibrator attached to said sound box, a disc having a serrated periphery bearing against said vibrator, means for rotating said disc, pivotally mounted cover actuating means, and two means spaced apart on said disc adapted to successively engage said cover actuating means and move the same, opening and closing said cover at pre-determined intervals.

3. A doll's voice for simulating the word "ma-ma" comprising a sound box having an opening therein, a cover for said opening, adapted to be closed against spring tension, a vibrator attached to said sound box, a disc having a flat portion on the periphery thereof, the remainder of the periphery being serrated, the serrated periphery being adapted to engage said vibrator, means for rotating said disc, pivotally mounted cover actuating means, and two means spaced apart on said disc adapted to successively engage said cover actuating means and move the same, opening and closing said cover at pre-determined intervals.

4. A doll's voice comprising a sound box having an opening therein, a cover for said opening, adapted to be closed against spring tension, a vibrator attached to said sound box, a housing fastened to the sound box, a disc rotatably mounted in said housing said disc having a serrated periphery bearing against said vibrator, means for rotating said disc, a plurality of spaced cams on said disc, cover actuating means pivotally mounted in said housing, two laterally spaced extensions on one side of the axis of said pivotally mounted cover actuating means, adapted to engage said cams, connecting means one end of which is fastened to said cover and the opposite end is fastened to said cover actuator at a point on the side of the axis of said actuator opposite to that of said extensions, and a stop adapted to limit the movement of said actuator in one direction by the spring tensioned cover.

5. A doll's voice for simulating the word "ma-ma" comprising a sound box having an opening therein, a cover for said opening, adapted to be closed against spring tension, a vibrator attached to said sound box, a housing fastened to the sound box, a disc rotatably mounted in said housing said disc having a flat portion on the periphery thereof, the remainder of the periphery being serrated, the serrated periphery being adapted to engage said vibrator, means for rotating said disc, two spaced cams projecting from one surface of said disc, cover actuating means pivotally mounted in said housing, two laterally spaced extensions on one side of the axis of said pivotally mounted cover actuating means, adapted to engage said cams, connecting means one end of which is fastened to said cover and the opposite end is fastened to said cover actuator at a point on the side of the axis of said actuator opposite to that of said extensions, and a stop adapted to limit the movement of said actuator in one direction by the spring tensioned cover.

STANLEY KRAKOWSKI.
